UNITED STATES PATENT OFFICE.

GEORGE W. GATES, OF GRAND RAPIDS, MICHIGAN, ASSIGNOR TO CHARLES B. JUDD, OF SAME PLACE.

CARPET-SWEEPER.

SPECIFICATION forming part of Letters Patent No. 284,833, dated September 11, 1883.

Application filed July 27, 1882. (Model.)

To all whom it may concern:

Be it known that I, GEORGE W. GATES, of the city of Grand Rapids, in the county of Kent and State of Michigan, have invented 5 certain new and useful Improvements in Carpet-Sweepers, of which the following is a specification.

My invention relates to improvements in carpet-sweepers; and the objects of my invention are as follows: To increase the efficiency 10 of a carpet-sweeper by improving the means by which the vertical adjustment of the brush-roller simultaneously at each end is obtained; the means of adjusting the brush-roller by the movement of the handle of the sweeper, and 15 to form a cheaper, simpler, and more durable device for dumping the dust from the sweeper. I attain these objects by means of the mechanism illustrated in the accompanying drawings, 20 in which—

Figure 1 is a plan view of that end of the sweeper in which the driving-wheels are placed. Fig. 2 is a plan view of the other end of the sweeper, and Fig. 3 is a perspective view of a bearing-block which forms a bearing 25 for one end of the brush-roller.

Similar letters refer to similar parts throughout the several views.

H represents the bail, attached to the plates 30 A and A', one on either end of the sweeper-case. The plates A and A' are each provided with a slot. (Shown by S and S' in the drawings.) In the end of the sweeper-case bearing the driving-wheels is a vertical slot, 35 through which the journal of the brush-roller projects into the slot in plate A, as shown in Fig. 1. Into the other end of the sweeper-case is fitted the bearing-block F, which block is provided with a groove, C, and ear E, which 40 ear forms the bearing for the end of the brush-roller. On block F is pin P, which projects through a vertical slot in the end of the sweeper-case and into the slot S' in plate A'. The object of using block F is to allow the easy removal 45 of the brush-roller. The plates A and

A' are rigidly attached to the bail H. The bail H may pass through the plates at the lower point of intersection into the sweeper-case, forming a bearing for the plates.

The drawings show the bail in a horizontal position. By lowering the bail the pin P and bearing E are raised, thereby raising and lowering the brush-roller. The dotted lines show the position of the several parts when the handle is lowered.

By this device the pressure on the carpet, as well as the increased friction, is regulated by the operator from the handle of the sweeper, the fulcrum being placed above the bearings of the brush-roller.

D D represents the door which covers the dust-opening. It may be a simple piece of metal, or any other suitable material, attached to the sweeper-case by the staples or hinges n, and so constructed as to open or shut freely.

The plate A may be made to project, as shown by X, so that it will slide or pass over the door D and hold it securely in position at all times, except when the handle is in a perpendicular position.

Having thus described my invention, what I claim to have invented, and desire to secure by Letters Patent, is—

1. In a carpet-sweeper, the plate A', provided with the slot S', in combination with 75 the bail H, block F, bearing P, and the brush-roller, substantially as described.

2. The combination of the plate A, having the slot S, and a projection, X, in combination with the door D D, for the purpose described. 80

3. In a carpet-sweeper, the handle attached to the ends of the sweeper, the fulcrum of said handle being above the brush-roller, in combination with said brush-roller, and suitable slots or notches, substantially as described.

GEORGE W. GATES.
